US00D623686S

(12) **United States Design Patent**
Gold et al.

(10) **Patent No.:** US D623,686 S
(45) **Date of Patent:** ** Sep. 14, 2010

(54) **INK STICK FOR PHASE CHANGE INK JET PRINTER**

(75) Inventors: **Christopher R Gold**, Tigard, OR (US);
William L Emery, Sherwood, OR (US);
Brent R Jones, Sherwood, OR (US)

(73) Assignee: **Xerox Corporation**, Norwalk, CT (US)

(**) Term: **14 Years**

(21) Appl. No.: **29/336,474**

(22) Filed: **May 5, 2009**

(51) **LOC (9) Cl.** **18-02**

(52) **U.S. Cl.** **D18/56; 347/88**

(58) **Field of Classification Search** D18/56;
347/88, 99; 106/31.29, 31.61

See application file for complete search history.

(57) **CLAIM**

The ornamental design for an ink stick for phase change ink jet printer, as shown and described.

DESCRIPTION

FIG. 1 is a top perspective view of an ink stick for phase change ink jet printer in accordance with the present invention;

FIG. 2 is a front view thereof;

FIG. 3 is a right end view thereof;

FIG. 4 is a rear view thereof;

FIG. 5 is a left end view thereof;

FIG. 6 is a top plan view thereof;

FIG. 7 is a bottom plan view thereof

FIG. 8 is a top perspective view of a second embodiment of the ink stick for phase change ink jet printer in accordance with the present invention;

FIG. 9 is a front view of FIG. 8;

FIG. 10 is a right end view of FIG. 8;

FIG. 11 is a rear side view of FIG. 8;

FIG. 12 is a left end view of FIG. 8; and,

FIG. 13 is a bottom plan view of FIG. 8, the top plan view being the same as FIG. 6.

The broken lines shown are for illustrative purposes only and form no part of the claimed design.

1 Claim, 8 Drawing Sheets

OTHER PUBLICATIONS

D7—Technology Review email regarding an Apr. 21, 2009-May 4, 2009 online brief publication of a photograph featuring 3 prototype Jupiter ink sticks.
P1—photograph of the recovered ink stick inventory.
P2—photograph of the recovered ink stick inventory.
P3—photograph of the recovered ink stick inventory.
P4—Apr. 23, 2009 page copies of Dodo-6666, web site of Ayad Al-Musawi.

P5—photograph of the only 16 otherwise confidential prototype ink sticks (confidential Jupiter program prototype ink sticks) found among the recovered stolen ink sticks.

P6—photograph of the only 16 otherwise confidential prototype ink sticks (confidential Jupiter program prototype ink sticks) found among the recovered stolen ink sticks.

P7—3 prototype Jupiter ink sticks in technology Review online publication.
